FUEL BURNER

Charles A. Reichelderfer, Rock Island, Ill., assignor to
Nu-Way Corp., Rock Island, Ill., a corporation of
Illinois

Filed Mar. 23, 1959, Ser. No. 55,114

Term of patent 14 years

(Cl. D81—2)

Fig. 1 is a perspective view of a fuel burner showing my new design, illustrating the top, rear and one side thereof;

Fig. 2 is a perspective view thereof as seen from the front and same side as shown in Fig. 1;

Fig. 3 is an elevational view, on a reduced scale, of the side of the fuel burner opposite that shown in Figs. 1 and 2.

I claim:

The ornamental design for a fuel burner, substantially as shown.
